UNITED STATES PATENT OFFICE.

DARWIN D. RANNEY, OF LEWISTOWN, ILLINOIS, ASSIGNOR TO HENRY W. PHELPS AND SARAH J. RANNEY, OF SAME PLACE.

CARBURETOR.

SPECIFICATION forming part of Letters Patent No. 437,454, dated September 30, 1890.

Application filed May 27, 1890. Serial No. 353,333. (No model.)

To all whom it may concern:

Be it known that I, DARWIN D. RANNEY, a citizen of the United States, residing at Lewistown, Illinois, have invented certain new and useful Improvements in Carburetors, of which the following is a specification.

My invention relates to certain improvements in a carburetor comprising two vessels concentrically arranged, the inner one bottomless and the outer one coverless, and containing a body of water supporting on its surface gasoline or other hydrocarbon oil, through which air is forced, and forms a vapor, which is conveyed away for heating or lighting.

15 A feature of my invention relates to novel means for regulating the vapor-pressure, said means comprising a valve or cock in the air-supply pipe, which is automatically controlled by the movement of the vapor-containing vessel.

Another feature of my improvement relates to novel means of supplying the oil to the inner vessel, and comprises a receptacle or tank in communication, by means of suitable pipes, 25 with the interior of said vessel, and which tank is refilled from barrels without interrupting the operation of the carburetor and without any exposure of the oil while it is being transferred. I effect this object by providing a conducting pipe or hose from the tank to the barrel or other receptacle containing the oil, and I also provide a branch air-pipe connecting with the main air-pipe and with the barrel or other oil-receptacle, so 30 that the air-current passing through the branch pipe is utilized to force the oil out of the barrel into the tank, and then by connecting the air-supply pipe with the top of the tank the oil may be forced out through suitable pipes and discharged into or upon the body of the water within the inner vessel.

In the accompanying drawings, Figure 1 is a central sectional elevation, the oil-barrel, tank, and a part of the pipe system being 45 shown in side elevation. Fig. 2 is a sectional plan view of the inner vessel of the carburetor and showing the outer vessel in plan, the section being taken on the line 2 2 of Fig. 1.

In the drawings, let A represent an outer

vessel open at the top, within which a bottomless vessel B is adapted to telescope, and having by preference the anti-friction rollers b, adapted to run on the guides C.

Beneath the closed top of the vessel B, which top is preferably conical in form, is placed suitable packing D, and when the vessel B has reached its lowest limit of movement this packing will rest upon and seal the open end of a pipe E, through which the vapor is conducted away to the place of use.

F represents an air-pipe, which will be connected at a point outside the vessel A with an air-pump, and is preferably conducted upwardly outside of the vessel A, and then descends through the space between the walls of the vessels A and B near to the bottom of A, and is thence carried inwardly, branching into the parts f'f''. Said branches deliver into the interior of the tank B below the water-line, (indicated at x x) At some convenient point in the air-pipe F, as at G, a valve is provided, and the valve-stem g is connected by a link H with the vessel B—as, for example, by means of the projecting rigid arm b'. It is evident now that as the vessel B is moved upwardly under the pressure of the forming vapor the valve will be operated through the intervention of the connecting-link and the air-supply will thus be cut off when the inner vessel has reached the point indicated by the dotted lines of Fig. 1. By this means the air-supply is automatically controlled, and as the vapor is withdrawn from the interior of the vessel B the latter begins to descend, opening, through the intervention of the link, the valve at G, so as to permit the passage of air and thus providing for the formation of the vapor by supplying air as fast as the vapor is withdrawn. The action is entirely automatic, and a uniform pressure of the vapor is thereby insured.

The hydrocarbon may be contained in any suitable receptacle—as, for example, the barrel I—and I transfer the oil from this barrel to an intermediate feed-tank, which is marked J. To accomplish this without interrupting the operation of the carburetor and without exposing the oil, I use by preference a flexi-

ble hose K, indicated by the dotted lines in Fig. 1, which hose communicates with the tank J, preferably near its top.

A branch pipe L taps the main air-pipe F 5 and communicates with the interior of the barrel I through the upper side, preferably by means of the short flexible section l. A cock l' is provided in this branch air-pipe in order to control the passage of air there- 10 through. A stub-pipe m is also provided at the top of the tank J, and the hose l is adapted to connect the branch pipe L and this stub m when desired.

An oil-supply pipe (marked N) leads from 15 the bottom of the tank J and is conducted up outside the vessel A, and thence descends through the space between A and B and is again upturned, delivering just below the water-line.

20 In operation, if the tank and barrel be both filled with oil and the vessel A filled with water to the line x x, before any vapor is formed the inner vessel B will be at the lowest limit of its movement, the packing resting on 25 top of the service-pipe. Now, if the pump be set in motion and the valves G and I' opened and the hose l connected with the stub m, the principal current of air will pass through the pipe F and be forced upwardly through the 30 water. At the same time a portion of the air-current will pass by way of the stub m and flexible hose l and will force the oil out through the pipe N, thus maintaining a layer of oil on top of the water, through which the 35 air will pass, thus enriching it and forming the vapor. This operation may be continued until the tank is exhausted, and then without stopping the pump a connection is made between the branch air-pipe L and the top of 40 the barrel, and the current of air will then force the oil out of the barrel into the tank.

The feature of automatically sealing the service-pipe when the inner vessel or holder is practically void of vapor is exceedingly

important, because if this be not done and a 45 jet or burner be flaming at any point along the line of the service-pipe the vapor contained in the pipe will be ignited and the flame will pass by way of the pipe into the carburetor and ignite the oil or vapor therein 50 and thus cause an explosion. While the vapor is forming in the holder the pressure therein is equal to or greater than the back-pressure in the service-pipe, and therefore ignition by way of the service-pipe is prevented.

55 I claim—

1. The combination, with a carburetor comprising two concentrically-arranged vessels, the inner one bottomless and the outer one coverless, of a tank to contain a hydrocarbon 60 oil and communicating by a suitable pipe with the inner vessel, an air-pipe to supply air under pressure to the inner vessel below the water-line, a barrel or equivalent receptacle to contain a supply of oil, and a branch 65 pipe adapted to be connected at will with the oil-supply vessel and with the top of the tank, whereby the oil may be transferred to the tank and forced thereout into the carburetor, substantially as described.

2. In a carburetor, the combination, with two vessels concentrically arranged, the inner one bottomless and the outer one coverless and adapted to contain water, of means for supplying oil to the inner vessel above 70 the water, a pipe to deliver air under pressure within the body of water in the inner tank, and a pipe to conduct away the vapor, said pipe having an open end terminating beneath 75 the top of the inner vessel and adapted to support the inner vessel at its lowest limit of movement and to be sealed thereby, substantially as described.

DARWIN D. RANNEY.
